UNITED STATES PATENT OFFICE

2,485,013

SNUBBED TRUCK

Raymond C. Pierce, Chicago, Ill.

Application November 3, 1944, Serial No. 561,669

23 Claims. (Cl. 105—197)

1

My invention relates to railway car trucks and more particularly to a truck incorporating snubbing means for dampening oscillations of the spring-supported truck bolster.

My invention is illustrated as applied to a truck of the type shown in a co-pending application, Serial No. 436,731, filed March 30, 1942, in the United States Patent Office in the name of David M. Light for "Car truck," and issued June 19, 1945, as Patent No. 2,378,414. This type of truck, particularly wherein the friction shoes are carried by the bolster, has proved to be an extremely practical design under service conditions, and it is the object of the present invention to incorporate certain features which facilitate the assembling and disassembling of the bolster and friction shoe unit with the truck side frame.

The general object of my invention is to design a truck of the above type in which the friction shoes are interlocked with the bolster in such manner as to permit slight rotation or rocking of the shoes as the bolster is removed from the bolster opening, thereby releasing the pressure of the shoes against the columns and at the same time maintaining the shoes in assembled relationship with the bolster in such manner that the shoes and bolster may readily be reinserted as a unit into the side frame bolster opening.

My invention comprehends a novel bolster and friction shoe unit wherein novel interlocking means is provided on the bolster and friction shoes, the shoe-actuating springs being housed within the bolster and being operable to urge said interlocking means into cooperative relation whereby the shoes are tilted or rotated in such manner that the friction faces of the respective shoes converge, thereby facilitating entrance of the unit into the side frame bolster opening.

My invention also comprises a novel bolster including a pocket in at least one side thereof, the bolster being formed with spaced diagonal ledges within the pocket, each ledge terminating at its outer extremity in a stop lug adapted for engagement with the associated friction shoe to limit outward movement thereof.

My invention also comprehends a friction shoe of novel form comprising a main friction wall with a spring seat wall and spaced ledge or wing portions projecting rearwardly therefrom, the ledge portions presenting wedge surfaces offset at their juncture with the main wall to afford stop means for engagement with complementary stop means on the bolster, and the spring seat wall presenting a spring seat sloping from the main wall in such manner as to facilitate the before-

2

mentioned tilting or rotating action of the shoe by accommodating relatively great spring pressure on the spring seat adjacent its front extremity.

In the drawings,

Figure 1 is a fragmentary side elevation of a railway car truck embodying my invention, portions of the structure being shown in section to clarify the illustration.

Figure 2 is a fragmentary top view of the structure shown in Figure 1 with the side frame illustrated in section through the column thereof.

Figure 3 is a sectional view of the bolster taken on the line 3—3 of Figure 2, and Figure 4 is an end view of the bolster.

Figure 5 is a sectional view taken on the line 5—5 of Figure 1.

Figures 6—8 inclusive illustrate in detail one of my novel friction shoes, Figure 6 being a bottom plan view thereof, Figure 7 being a side elevation thereof, and Figure 8 being a rear elevation.

Describing my invention in detail, the side frame is of conventional type comprising tension and compression members 2 and 4 and a column 6 merging therewith adjacent each end of the frame to define a bolster opening 10 with a widened upper portion indicated at 12.

The tension member 2 is of conventional design and is of box section beneath the bolster opening with the top chord 14 widened and formed at each of the inboard and outboard sides thereof with an upstanding flange 16 affording convenient confining means for the bolster supporting coil springs diagrammatically indicated at 18, 18, said springs affording support in the usual manner for a bolster generally designated 20.

The bolster, as may be clearly seen from a consideration of Figures 2—4 inclusive, is a box-section member comprising top and bottom walls 22 and 24 merging at each side of the bolster with

40 a side wall 26 formed with inboard and outboard interlocking lugs or gib 28 and 30 for cooperation with the column 6 to afford an interlock between the side frame and the bolster. It will be readily understood by a comparison of Figures 1 and 4 that the outboard gib 30 is of less depth than the widened upper portion 12 of the bolster opening so that the bolster may be elevated therein and removed therefrom during a quick wheel change as hereinafter more fully described.

At each side thereof the bolster is formed with a friction shoe pocket 32 defined by the inboard and outboard walls 34 and 36 and the rear wall 38, all of said walls 34, 36 and 38 extending between the top and bottom walls 22 and 24 and merging therewith to define a sturdy box-section

structure. Each of the inboard and outboard walls 34 and 36 is offset to define a ledge 40 having a crowned wedge face in engagement as at 42 (Figures 1 and 5) with a corresponding ledge or wing portion 44 of the associated friction shoe generally designated 46 and hereinafter described in detail. It may be noted that each ledge 40 terminates at its outer extremity in an upstanding lug 48 affording a diagonal abutment surface 50, said surface 50 functioning as stop means for the associated friction shoe 46, as hereinafter more particularly set forth.

The friction shoe is illustrated in detail in Figures 6-8 wherein it will be seen that the shoe comprises a front or main friction wall 52 affording a front friction face 54 for frictional engagement as at 56 with a wear plate 58 mounted in any convenient manner as by welding on the adjacent column 6. Projecting rearwardly from the main wall 52 of the friction shoe is a spring seat wall 60 affording a spring seat 62 sloping downwardly from the main wall 52 as will be clearly seen in Figures 1 and 7, and also projecting rearwardly from the main wall 52 are the spaced before-mentioned ledges 44, 44 merging with a rear wall 64, said ledges presenting on their lower edges diagonal wedge surfaces 66, 66 for engagement at 42 with the associated bolster ledges 40, 40, as heretofore described. Each of the wedge surfaces 66 is offset to afford an abutment or stop surface at 68 adapted to abut against the associated stop surface 50 under the conditions hereinafter described.

The friction shoe 46 is actuated by a substantially vertical spring 70 compressed between and bearing against the top wall 22 of the bolster and the spring seat 62 of the friction shoe, and it may be noted at this point that the before-mentioned sloping of the spring seat 62 affords relatively great pressure adjacent the forward edge thereof, whereby as the bolster is elevated in the bolster opening for removal therefrom, the rocking action of the shoe is facilitated, thereby urging the stop surfaces 68, 68 of the shoe into abutment with the complementary surfaces 50, 50 of the bolster. It may also be noted that this rotating or rocking action of the shoe is due to the fact that the longitudinal axis of the spring 70 is disposed outwardly of the points of contact at 42 between the friction shoe and bolster wedge surfaces, as may be clearly seen in Figure 1. This arrangement of the spring in combination with the crowned wedge surfaces of the ledges 40, 40 causes the before-mentioned rotating action.

Indicated in phantom lines in Figure 1 at the top of the bolster opening is the bolster and friction shoe unit illustrated in position preparatory to assembling or disassembling the unit with respect to the side frame. The bolster in its elevated position in Figure 1 is indicated at 20A and the friction shoe is indicated at 46A, the shoe actuating spring being indicated at 70A; and it may be noted that in this elevated position of the bolster and friction shoe unit, the complementary stop means 50 and 68 of the bolster and shoe respectively are in engagement at 72, thereby limiting the rotational movement of the shoe and maintaining it in stable position relative to the bolster so that the bolster and shoe constitute a unit which may be conveniently assembled and disassembled with respect to the side frame. It may also be noted that the friction shoe in its tilted or rotated position, as shown at 46A, is afforded slight clearance from the wear plate 58 so that under these conditions there is no frictional

engagement between the shoe and the wear plate, thus readily accommodating insertion of the bolster and friction shoe unit into the bolster opening or removal of the unit therefrom.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claims.

I claim:

1. In a railway car truck, a side frame with spaced columns partly defining a bolster opening having a widened upper portion, a spring group on said frame in said opening, a bolster supported by said group, said bolster comprising inboard and outboard guide lugs cooperating with each column to afford an interlock between the side frame and the bolster, the outboard lugs being of less depth than the widened upper portion of the bolster opening to accommodate removal of the bolster during quick wheel change, a pocket in each side of the bolster adjacent the associated column, a diagonal ledge on said bolster within said pocket, a spring seat integrally formed on said bolster in vertically spaced relationship to said ledge, a friction shoe having a wedge face in rockable engagement with said ledge, and a friction face engaging said associated column, a compressed substantially vertical spring reacting against said seat and against an aligned abutment surface on said shoe, the longitudinal center line of said spring being spaced outwardly from the point of contact between said wedge face and said ledge whereby upon elevation of said bolster in said bolster opening to the widened upper portion thereof said shoe is caused to rock on said ledge thereby causing said friction face to become disengaged from the associated column, and cooperating stop means on said shoe and said bolster for limiting the rocking movement of said shoe.

2. In a railway car truck, a side frame with spaced columns partially defining a bolster opening having a widened upper portion, a spring group on said frame in said opening, a bolster supported on said group, said bolster comprising guide means of less depth than the widened upper portion of said bolster opening in interlocking engagement with said columns, a pocket in each side of the bolster adjacent the associated column, spaced diagonal ledges on said bolster within said pocket, a spring seat integrally formed on said bolster in vertically spaced relation to said ledges, a friction shoe having spaced wedge faces rockably engaging respective ledges, and a friction face engaging said associated column, a compressed substantially vertical spring extending between said ledges and said wedge faces, said spring reacting against said seat and an aligned abutment surface on said shoe, and cooperating stop means on said shoe and said bolster adjacent the outer extremity of said pocket for limiting the rocking movement of the shoe, the longitudinal center line of said spring being spaced outwardly from the points of contact between said wedge faces and said ledges whereby upon elevation of said bolster in said bolster opening to the widened upper portion thereof said shoe is caused to rock on said ledges, thereby causing said friction face to become disengaged from the associated column.

3. In a railway car truck, a side frame having tension and compression members and spaced columns defining therewith a bolster opening, a

bolster spring-supported in said opening, said bolster having at each side thereof a pocket with a diagonal web therein, each of said pockets housing snubbing means including an auxiliary spring and a wedge shoe rockably engaging the associated web, said auxiliary spring urging said shoe into said rocking engagement with the associated web and into frictional engagement with the adjacent column, the bearing between said shoe and the associated web being eccentric with respect to the axis of said auxiliary spring whereby elevation of said bolster above normal operating position in said opening automatically permits said auxiliary spring to rock said shoe to a fixed inoperative position as said bolster approaches the top of said opening, and interengaging means on said shoe and said web limiting the rocking movement of said shoe and limited sliding movement thereof against the associated web.

4. In a railway car truck, a side frame having tension and compression members and spaced columns partially defining therewith a bolster opening, guide surfaces on the adjacent edges of said columns intermediate the upper and lower extremities thereof, a bolster spring-supported in said opening, snubbing means housed in each side of said bolster including an auxiliary spring and a wedge shoe bearing against said spring and rockably seated against wedge means in the bolster, said auxiliary spring being operable to urge said wedge shoe along said wedge means into engagement with the associated guide surface, the bearing between said shoe and said wedge means being eccentric with respect to the axis of said auxiliary spring whereby movement of said bolster to a point vertically spaced with respect to the normal operating position thereof automatically permits said auxiliary spring to rock said shoe to a fixed inoperative position within the bolster, and means on said bolster for engaging said shoe to limit relative sliding and rocking movement of the latter against said wedge means.

5. In a railway car truck, a side frame having spaced columns partially defining a bolster opening, a bolster resiliently supported in said opening, snubbing means housed within said bolster adjacent each column, each of said snubbing means including an auxiliary spring compressed against a portion of the bolster and a friction shoe bearing against said spring, said shoe having frictional engagement with the adjacent column and having rockable wedge face bearing with a diagonal wedge surface within the bolster, the bearing of said shoe against said wedge surface being eccentric with respect to the axis of said auxiliary spring whereby said spring may automatically rotate said shoe about said bearing to a fixed position within said bolster as the latter is moved vertically from its normal operating position within the bolster opening, and means on said bolster for engaging said shoe to limit relative sliding and rocking movement of the latter against said wedge surface whereby said shoe is maintained in said fixed position.

6. In a railway car truck, a side frame comprising a column, a bolster resiliently supported from said frame adjacent said column, said column comprising a friction surface, wedge means in rockable wedge engagement with the bolster and in frictional engagement with said surface, resilient means compressed at opposite ends thereof against abutment means on said bolster and wedge means respectively, and spaced abut-

ment surfaces on said bolster and wedge means respectively, said resilient means being so arranged that its longitudinal axis is closer to said column than the point of contact between said bolster and wedge means whereby when the bolster is moved vertically to disengage said wedge means from said friction surface, said resilient means is operable to rotate said wedge means to a point at which said abutment surfaces become engaged to limit the rotational movement of the wedge means.

7. In a railway car truck, a side frame having spaced columns partially defining a bolster opening, a bolster spring-supported in said opening, snubbing means housed in each side of said bolster, each of said snubbing means including an auxiliary spring, and a friction shoe having rocking engagement with a diagonal wall of said bolster and having flat face engagement with the adjacent column, the bearing of said shoe against said wall being eccentric with respect to the axis of said auxiliary spring whereby said spring may automatically rotate said shoe about said bearing to a fixed position within said bolster as the latter is elevated to the top of said opening, and interengaging means on said shoe and said wall limiting the rotational movement of said shoe.

8. In a friction shoe and bolster assembly for a railway car truck, a bolster with a pocket therein, spaced diagonal ledges on said bolster in said pocket, each of said ledges having a wedge surface terminating at its outer end in a stop lug with an abutment surface angularly related to said wedge surface, a friction shoe in said pocket having spaced wing portions in wedge engagement with the wedge surfaces of respective ledges, each of said wing portions comprising a diagonal face opposed to the associated abutment surface, and resilient means compressed between a wall of said bolster and a portion of said shoe, said resilient means extending between said spaced ledges and between said spaced wing portions.

9. In a friction shoe and bolster assembly for a railway car truck, a bolster having a pocket therein, a friction shoe within said pocket, said shoe and said bolster having complementary abutting wedge means in rockable interengagement, cooperating stop means integrally formed with said shoe and bolster respectively for limiting relative rocking movement therebetween along said wedge means, a spring seat on said bolster within said pocket, a spring seat on said shoe, and resilient means under compression between said seats, said resilient means being so arranged that the longitudinal axis thereof is disposed laterally of the point of contact between said wedge means, one of said spring seats being diagonally arranged with respect to the other thereof.

10. In a friction shoe and bolster assembly for a railway car truck, a bolster having a pocket therein, a friction shoe within said pocket, said shoe and said bolster having abutting wedge means in rockable interengagement, cooperating stop means integrally formed with said shoe and bolster respectively for limiting relative rocking movement therebetween along said wedge means, a spring seat on said bolster within said pocket, a spring seat on said shoe, and resilient means under compression between said seats, said resilient means being so arranged that the longitudinal axis thereof is disposed laterally of the point of contact between said wedge means.

11. In a friction shoe and bolster assembly for

a railway car truck, a bolster, a friction shoe carried thereby, said shoe and bolster having abutting wedge surfaces, cooperating stop means integrally formed on said shoe and bolster respectively for limiting relative downward movement of said shoe along said surfaces, a substantially horizontal spring seat integrally formed with said bolster, a diagonal spring seat on said shoe below said first-mentioned seat, and resilient means under compression between said seats.

12. In a friction shoe for a railway car truck, a hollow member with a substantially vertical front wall comprising a front friction face, a spring seat web projecting rearwardly from said wall and presenting a spring seat, and spaced ledges projecting rearwardly from said wall and comprising respectively wedge surfaces sloping toward said wall, each of said wedge surfaces being offset adjacent said wall to afford an abutment angularly related thereto.

13. In a friction shoe for a railway car truck, a hollow member with a front wall comprising a friction face, a web projecting rearwardly from said wall and presenting a sloping spring seat, and a ledge projecting rearwardly from said wall and comprising a wedge surface sloping therefrom, said wedge surface being offset adjacent said wall to afford an abutment angularly related to said wedge surface.

14. In a railway car truck, a side frame, a bolster spring-supported therefrom, a friction shoe housed within the bolster in wedge engagement therewith and in frictional engagement with a portion of said frame, a resilient actuating means for said shoe housed within said bolster in abutment therewith, and cooperating stop means integrally formed on said bolster and said shoe for limiting outward movement of the latter, said resilient means being operative upon engagement of said stop means to rotate said shoe to a diagonal position in said bolster facilitating clearance of said shoe from said frame portion upon elevation of said bolster for removal from said side frame.

15. In a friction shoe and bolster assembly for a railway car truck, a bolster, a friction shoe housed therewithin, said shoe and bolster having abutting wedge surfaces, cooperating stop means integrally formed on said shoe and bolster respectively for limiting movement of said shoe outwardly of said bolster along said surfaces, and resilient means under compression between portions of said shoe and said bolster, said resilient means being operative upon engagement of said stop means to rotate said shoe to a diagonal position in said bolster facilitating application or removal of said assembly from an associated side frame.

16. In a bolster for a railway car truck, a member with a friction shoe pocket in at least one side thereof, a sloping wedge face on said member within said pocket merging at the outer extremity thereof with a reversely sloping abutment surface adapted to act as stop means for an associated friction shoe, and a spring seat on said bolster within said pocket, said seat being vertically spaced with respect to said face and facing the same, said wedge face being crowned and relieved at the edge adjacent said surface to accommodate tilting of an associated friction shoe.

17. In a bolster for a railway car truck, a box-section member with a friction shoe pocket in at least one side thereof, a ledge integrally formed with said member in said pocket, said ledge sloping toward the outer extremity of said pocket and

terminating in a stop lug for an associated friction shoe, and a spring seat on said bolster within said pocket, said seat being in vertically spaced relationship with respect to said ledge and facing the same, said ledge being crowned and having a relieved portion adjacent said lug to accommodate a tilting movement of an associated friction shoe.

18. In a railway car truck, a side frame, a bolster spring-supported therefrom, a friction shoe in wedge engagement with a crowned surface on said bolster and in frictional engagement with a portion of said frame, resilient means compressed between said bolster and said shoe for actuation of the latter, and means on said bolster adapted for engagement with said shoe to maintain the shoe in assembled relationship with said bolster when the latter is dissociated from said frame, said resilient means being operative upon engagement of said shoe with said means on said bolster to tilt said shoe along said crowned surface to an inclined position facilitating its disengagement from said frame as said bolster is elevated in said frame for removal therefrom.

19. In a friction shoe for a railway car truck, a hollow member with a front wall comprising a friction face, a web projecting rearwardly from said wall and presenting a spring seat angularly related thereto, and a ledge projecting rearwardly from said wall and comprising a wedge surface angularly related thereto and to said seat, said wedge surface being offset adjacent said wall to afford an abutment angularly related to said wedge surface and adapted for interlocking engagement with an associated truck part.

20. In a friction shoe and bolster assembly for a railway car truck, a bolster, a friction shoe supported therein, said shoe and bolster having abutting wedge surfaces, one of said wedge surfaces having a crowned face, cooperating stop means integrally formed on said shoe and bolster respectively for limiting movement of said shoe along said surfaces, a substantially horizontal spring seat on said bolster, an opposed diagonally arranged spring seat on said shoe, and resilient means under compression between said seats.

21. In a friction shoe and bolster assembly for a railway car truck, a bolster, a friction shoe supported therein, said shoe and bolster having abutting wedge surfaces, cooperating stop means integrally formed on said shoe and bolster respectively for limiting movement of said shoe along said surfaces, a substantially horizontal spring seat on said bolster, an opposed diagonally arranged spring seat on said shoe, and resilient means under compression between said seats, said resilient means being operative to tilt said shoe with respect to said bolster upon engagement of said stop means.

22. In a friction shoe and bolster assembly for a railway car truck, a bolster, a friction shoe supported therein, said shoe and bolster having abutting wedge surfaces, cooperating stop means integrally formed on said shoe and bolster respectively for limiting movement of said shoe along said surfaces, a substantially horizontal spring seat on said bolster, an opposed diagonally arranged spring seat on said shoe, and resilient means under compression between said seats, whereby one end of said shoe is withdrawn inwardly of said bolster and the other end thereof projected outwardly therefrom to facilitate application or removal of said assembly with respect to an associated side frame.

23. In a friction shoe for association with a bolster in a railway car truck, a hollow member with a front wall comprising a friction face, a web projecting rearwardly from said wall and presenting a spring seat angularly related thereto, and a ledge projecting rearwardly from said wall and comprising a wedge surface angularly related thereto and to said seat, said wedge surface being offset adjacent said wall to afford an abutment angularly related to said wedge surface and adapted for interlocking engagement with an associated truck part, the bottom wall of said shoe being chamfered at one edge thereof to accommodate tilting within said bolster under certain operating conditions.
